(57) **CLAIM**

The ornamental design for a vehicle wheel, toy vehicle wheel, and/or replicas thereof, as shown and described.

DESCRIPTION

FIG. 1 is a perspective view of a vehicle wheel, toy vehicle wheel, and/or replicas thereof according to the design; FIG. 2 is an additional perspective view thereof; FIG. 3 is an additional perspective view thereof; FIG. 4 is a front view thereof; FIG. 5 is a rear view thereof; and, FIG. 6 is a side view thereof.

The claimed design is indicated by the relatively dark portions in the figures. The rear portions viewed in FIG. 5 are shown as de-emphasized and in a relatively lighter gray scale and form no part of the claimed design.
